(57) **CLAIM**

The ornamental design for buttons for game controller as shown and described.

DESCRIPTION

FIG. 1 is a front view of buttons for game controller showing my new design;

FIG. 2 is a rear view thereof;

FIG. 3 is a left view thereof; and,

FIG. 4 is a right view thereof.

The broken lines shown in the figures are for the purpose of illustrating portions of the buttons for game controller that forms no part of the claimed design.

1 Claim, 4 Drawing Sheets

FIG. 1

FIG. 2

FIG. 3

FIG. 4
